UNITED STATES PATENT OFFICE.

ALEXANDER McALLISTER AND THOMAS LOGAN, OF HANNA, WYOMING.

TRUCK.

1,064,513.

Specification of Letters Patent. Patented June 10, 1913.

Application filed July 20, 1912. Serial No. 710,572.

To all whom it may concern:

Be it known that we, ALEXANDER McALLISTER and THOMAS LOGAN, citizens of the United States, residing at Hanna, in the county of 5 Carbon and State of Wyoming, have invented new and useful Improvements in Trucks, of which the following is a specification.

This invention relates to trucks and more 10 particularly to that type of trucks adapted to transport coal cars up inclines out of mines.

The principal object of the invention is to 15 provide a simple and efficient device of this character which is adapted for receiving coal cars from lateral leads and transporting them up inclines.

A further object of the invention is to 20 provide a truck of this character having adjustable platforms which will adapt the truck for inclines of different pitch, whereby the cars will be held in horizontal position at all times.

Further objects of this invention will appear 25 as the following specific description is read in connection with the accompanying drawing, which forms a part of this application and in which:—

Figure 1 is a top plan view. Fig. 2 is a 30 side elevation. Fig. 3 is a detail sectional view.

In Figs. 1 and 2 of the drawings, the track 1 is shown on an incline which may lead to the outside of the mine or to any 35 other suitable point. Leading into these tracks at right angles are other tracks shown at 2 which are arranged in the lateral lead for the transportation of coal cars from said lateral leads to the inclined leading to 40 the outside of the mine. The above statement gives the general idea of the manner of employing a truck to be hereinafter described in connection with mines having inclined shafts and lateral leads connecting 45 the same. It will here be stated that the employment of the truck to be described obviates the use of expensive switches and operating the apparatus.

The truck comprises a rectangular frame 50 3 formed of any suitable material and having sufficient strength to withstand the strain to which it is subjected. This frame is mounted upon wheels 4 adapted to run upon the rails of the track 1. Extending 55 transversely across the frame are separated

shafts 5 and 6, to each of which are pivoted platforms 7 and 8, each having a depending rear piece 9 and which carries suitable mechanism for raising and lowering the rear end of the platform. These platforms 60 have mounted thereon the rails 10 and are preferably provided with some form of locking mechanism which will engage the axle of the cars and hold the same against movement laterally of the truck. A conventional 65 form of locking mechanism is here shown in the form of pivoted spring pressed pawls or dogs 11 which engage the axles of the car.

The mechanism for raising and lowering the free ends of the platforms may also consist of any suitable mechanism, a conventional structure being here shown in the form of a rack bar operated by a worm and worm wheel.

The forward end of the truck has secured 75 thereto a rope or cable 12 having a hook 13 at its outer end which is adapted to engage the ties of the track 1 or suitable projections 14 projecting therefrom. This means is provided in order that the truck may be held 80 in stationary position with its tracks in alignment with the tracks 2 of the lateral leads. When the cars are pushed on to the truck from the lateral leads, pivoted dogs at the receiving side of the truck will be depressed until the car axles pass the same, at 85 which time they will be raised so as to lock the cars against movement laterally on the truck.

What is claimed is:—

1. A car carrying truck comprising a wheeled frame, platforms pivoted at one end to the frame and having their surface inclined with relation to the frame, tracks carried by the platform, and means for raising 95 and lowering the free end of the platform.

2. A car carrying truck comprising a wheeled frame, platforms pivoted at one end to the frame and having their surface inclined with relation to the frame, tracks carried by the platform, and means for locking 100 cars on the tracks against lateral movement over the platform.

In testimony whereof we affix our signatures in presence of two witnesses.

ALEXANDER McALLISTER.
THOMAS LOGAN.

Witnesses:

EDW. MCATEE,
Mrs. ED. MCATEE.
